SET OF DICE FOR A GOLF GAME

Burnham G. Preston, Winchester, Mass.

Application November 1, 1954, Serial No. 32,891

Term of patent 7 years

(Cl. D34—5)

Fig. 2.

Fig. 1.

Fig. 3.

Fig. 5.

Fig. 7.

Fig. 1 is a perspective view of one die in a set of dice for a golf game, showing my new design;

Fig. 2 is an unfolded view of the six sides of the die of Fig. 1 showing all of the designs thereon;

Fig. 3 is a perspective view of the second die of the set showing the design on three of the sides;

Fig. 4 is an unfolded view of the six sides of the die in Fig. 3 showing all of the designs thereon;

Fig. 5 is a perspective view of the third die in the set showing the design on three of the sides;

Fig. 6 is a view of the six sides of the die of Fig. 5 unfolded to show the designs appearing thereon; and

Fig. 7 is an enlarged fragmentary sectional view of the die of Fig. 3 taken on the line 7—7 of Fig. 4.

I claim:

The ornamental design for a set of dice for a golf game, as shown.
